UNITED STATES PATENT OFFICE.

FREDERICK WILL, OF ROCHESTER, NEW YORK.

STOVE.

SPECIFICATION forming part of Letters Patent No. 341,363, dated May 4, 1886.

Application filed April 30, 1883. Serial No. 93,378. (No model.)

To all whom it may concern:

Be it known that I, FREDERICK WILL, of Rochester, Monroe county, New York, have invented a certain new and useful Improvement 5 in Stoves; and I do hereby declare that the following is a full, clear, and exact description of the same, reference being had to the accompanying drawings, in which—

Figure 1 is a longitudinal vertical section 10 of a stove, showing my improvement. Fig. 2 is a cross-section of the same in line $x x$ of Fig. 1, enlarged. Fig. 3 is a similar view in line $y y$. Fig. 4 is a similar view in line $z z$. Fig. 5 is a vertical section in line $w w$ of Fig. 2.

15 My improvement relates to parlor-stoves of square form in cross-section; and it consists of such a stove provided with a circular fire-pot and a removable magazine, and having four reversible flues, at the four corners, of peculiar 20 construction, as hereinafter described.

This stove is of the form of ordinary square parlor-stoves well known. Heretofore in such stoves a square or oblong fire-pot has been used, conforming to the square or oblong outline of the stove. In place of such square fire-pot I employ a circular one, similar to that used in cylindrical stoves, and I employ, in addition thereto, a downward flue in each corner of the square stove, which flues have a 25 circuitous connection with the base, from which the products of combustion after heating the base pass off through an exit-flue in the rear to the smoke-pipe.

In the drawings, A shows the body of the 35 stove, which is square in cross-section, and B is the circular fire-pot, resting loosely therein on flanges $a a$, so that it can be readily removed upward and taken out bodily through the door b , which is of sufficient size for the 40 purpose.

C is the magazine, resting at its top on flanges $c c$, and is also removable. In removing the fire-pot it is necessary to first remove the magazine.

45 D D and D' D' are the four reversible flues in the four corners of the stove. They open from above the fire-pot and extend down vertically, and carry the heat and the products of combustion down into the hollow base E by 50 the following means:

G G are two horizontal flues at the sides of the stove just above the base, which extend

from front to rear. They are shown more particularly in the cross-section, Fig. 3, and vertical section, Fig. 5, and are indicated by the dotted lines in Fig. 2. The vertical flues D D do not extend through the horizontal flues, but simply open into them at their ends. At the rear ends of the horizontal flues are ports or openings $d d$, which open downward through 60 the plate and communicate with the base E. The ports come directly under the rear vertical flues, D' D', so that the currents from the latter have a direct and straight course down into the base; but the currents from the front 65 vertical flues, D D, have an indirect course, first passing into the end of the horizontal flues, and thence passing along the whole length of these horizontal flues, and finally passing down the ports $d d$, uniting in common with the volume from the rear vertical flues. By this means the sides of the stove 70 are heated. In the hollow base are two vertical plates, H H, as shown in the cross-section, Fig. 4, and as indicated by the dotted lines in Fig. 3. These plates are set near the sides at the rear, but converge toward the front. These plates form flue-passages in the base on each side, receiving the draft from each of the ports d , conducting it forward to 75 the front of the stove, and then, after it has passed the front end of the plates, turning it inward between the plates, as indicated by the arrows in Fig. 4, where it finally escapes up the back flue of the stove. 85

f is a central port or passage opening from the rear of the hollow base up through the top plate into the back flue, I, of the stove, through which flue the products of combustion, after escaping from between the plates in the base, 90 pass, and finally escape through a smoke-pipe, K, into the chimney. Above the back flue is a boiler-opening, g, which receives heat from an open space, h, above the fire-pot.

The construction of the flues, as above described, is especially adapted to a square stove provided with a circular fire-pot. The corners left by the circle of the fire-pot furnish ample space for the vertical flues. The latter conduct the heat down into the horizontal 100 flues, and here, owing to the fact that the front ends of the horizontal flues are closed and the rear ends alone have discharge-passages into the base, the heat which passes down the front

vertical flues has an extended passage at the sides of the stove, which keeps said sides constantly heated—an effect not accomplished in ordinary square stoves of the kind. On entering the hollow base through the ports *d d* the heat is again turned forward by the plates *H H*, and is again turned backward between the plates, and thus a zigzag course is made forward and back, which is most effective in extracting the heat before the final escape.

In the throat, between the fire-space *h* and the back flue, *I*, is a valve and deflector, constructed as follows: *k* is a fixed plate set in an inclined direction across said throat, one edge *l* connecting with the top plate of the fire-pot support, the other edge connecting with the flue-plate above the smoke-pipe *K*, as shown in Fig. 1. On top of the fixed plate is a sliding plate, *l*, of similar form, and provided with a stem, *m*, which extends outward through the stove, and by which the sliding plate is operated. Both plates are provided with ordinary register openings or slots, *n n*, as shown in Fig. 2. By sliding the upper plate the register may be opened, in which case the direct draft from over the fire-pot can pass straight to the smoke-pipe without passing through the reversible flues; or by sliding it the other way the register can be closed, thereby forcing the draft to pass down the reversible flues and take the indirect course before described. By this means, even when the register is closed and the draft is passing through the downward flues, the heat from the fire always passes directly through the open space *h* to the boiler, which is not the case where an ordinary shifting valve is used, which covers one flue as it uncovers the other. Another advantage results from the inclined position of the regis-

ter-valve, which serves as a deflector to throw 40 the heat upward to the boiler.

Having described my invention, I claim—

1. In a square stove having a removable fire-pot, the combination of the four reversible flues *D D' D' D'* in the four corners of the 45 stove, the two horizontal flues *G G* at the sides of the stove just above the hollow base, and the ports or passages *d d* through the top plate of the base, the two front vertical flues opening down into the ends of the horizontal 50 flues, and the two rear vertical flues opening directly down into the base through the ports *d d*, as herein shown and described.

2. In a square stove having a removable fire-pot, the combination of the four reversible flues *D D' D' D'* at the corners of the stove, the two horizontal flues *G G* at the sides of the stove, the ports or passages *d d*, opening through the top plate of the base and located directly under the rear vertical flues, and the 60 two side flues in the hollow base formed by the plates *H H*, as herein shown and described.

3. In a square stove, the combination, with the fire-pot *B* and the discharge-flue *I*, of the register-plates *k l*, extending angularly across 65 the flue and resting above the exit-pipe *K*, and a seat provided with a boiler-hole above the register, with a clear passage extending from the fire-chamber to the boiler-hole, as shown and described, and for the purpose 70 specified.

In witness whereof I have hereunto signed my name in the presence of two subscribing witnesses.

FREDERICK WILL.
